Specification of Letters Patent. Patented Dec. 22, 1914.

Application filed December 10, 1913. Serial No. 805,780.

To all whom it may concern:

Be it known that I, JAMES A. MURPHY, a citizen of the United States of America, residing at Holyoke, in the county of Hampden and State of Massachusetts, have invented certain new and useful Improvements in Heels, of which the following is a specification.

This invention relates to improvements 10 in the construction of boots and shoes, and particularly in the construction of a heel. At the present time it is common practice, on boots and shoes, instead of having the entire heel composed of leather, to have a 15 portion of the heel made of rubber or other elastic material.

One of the objections to applying or securing the rubber heel in place is that it takes considerable length of time for the 20 rubber cement to set before the rubber heel is attached. This delay in attaching rubber heels is objectionable for the reason that a great many times a person desires to have a set of rubber heels attached with as little delay as possible. The present invention is 25 therefore, designed to overcome this objection.

The invention proper consists in forming the rubber part of the heel with projections. 30 These projections are designed to enter the lowermost lift of the heel and further, they are designed to take the place of cement. That is to say, the projection will hold the rubber and the leather parts together without employing cement at all and when the heel is finally secured in place by means of nails the finished article is as rigid and firm as if cement had been used.

Referring to the drawings: Figure 1 is a 40 top plan view of the rubber heel, showing the projections and the upper surface thereof. Fig. 2 is a side elevation of Fig. 1, looking from the left, clearly showing the projections beyond the upper surface of the heel. Fig. 3 is a top plan view of the leather which is formed with openings to receive the 45 projections of the rubber heel. Fig. 4 shows the plan view after the assemblage of the leather and rubber. Fig. 5 is a sectional view on the line 5—5 of Fig. 3, showing the openings therein. Fig. 6 is an edge elevational view of Fig. 4, showing the rubber and leather assembled. Fig. 7 is a transverse sectional view on the line 7—7 of the 50 Fig. 4, illustrating the projections of the

rubber part located in the openings of the leather part. Fig. 8 is a modification, showing the leather part as comprising the single strip of leather having an opening in the center thereof, and the opening in the strip 60 designed to receive the projections of the rubber part and also showing the nails or securing means passing through the projections, and through the openings in the leather strip, whereby the rubber is expanded by means of the securing means to 65 completely fill the openings in the strip of leather. Fig. 9 is a detailed plan view of the leather insert or strip piece. Fig. 10 is a modification.

Referring to the drawings in detail, 70 10 designates the rubber heel proper formed with conical projections 11 on the upper surface 12.

13 designates holes for receiving the usual 75 securing means, 14 is the leather or lift which is formed with the openings 15 to receive the projections 11 of the rubber heel and also the openings 16 which register with the openings 13, and through which pass the 80 securing nails or other device.

In Fig. 4 the projections 11 are shown 85 located in the openings 15 of the leather lift. It will be seen from this construction that after the leather lift 14 and the rubber heel 10 are assembled and securely nailed to the heel of the shoe that the projections 11 will serve to retain the rubber heel part 10 in place as effectually as if the two members 10 and 14 had been cemented together. It is, of course, understood that the leather lift 14 is made slightly larger than the rubber part of the heel; so that after the 90 assembling or securing of the lift 14 and the rubber part 10 to the shoe the two can be buffed or smoothed down to an even surface to present a finished appearance. This means of attaching a rubber heel saves 95 a great deal of time in that it is not necessary for the cement to dry before the rubber part is attached to the leather part. The piece 14 can be cut from an accurately formed die with the opening 15 therein, and the rubber heel 10 can be furnished with the projections 11 and molded therewith and the repairer is only required to assemble the two parts and secure the same to the shoe after the heel part has been leveled or removed a definite amount.

Referring to the modification shown in

Figs. 8 and 9, the lift part, instead of being formed of a solid member is made in the form of the strip indicated at 17 and this strip is formed with openings 18 which receive the conical shaped projections 13 of the rubber heel. The center part of the lift is left open as indicated at 19. In this form the securing means are driven through the projections 11 and also through the openings 18 of the strip 17. The purpose of locating the securing means indicated at 20 in the projections 11, is to expand the same so that they will completely fill the openings 18 and thus secure a very tight fit between the projections and the opening. Another advantage of this modification is that an air space 21 is provided between the rubber heel 10 and the part 22 of the heel construction. It is of course understood that other modifications and forms are comprised within the disclosure already made, and I do not limit myself to the specific constructions herein shown and described, or to leather and rubber but also include similar material. It is to be understood that the projections 11 are only one form that I may use, and if found desirable ribs in the upper surface of the rubber heel 10 may be used instead of projections. These ribs may be of any shape or length desired, it being understood that correspondingly shaped openings will be formed in the lift member 14 to receive these ribs.

Referring to the modification shown in Fig. 10, the center portion 19, of the lift

portion 14, receives the upwardly projection portion 23 of the rubber heel and completely fills the same as shown. In this form the nails 20 pass through the projections 11, of the rubber heel to expand the projections 11 and cause the same to completely fill the openings 18. In this form the projection 23 assists in retaining the rubber portion 24 in place.

Other obvious forms and modifications are understood to be included which are not herein shown and described.

What I claim is:

1. A heel construction, comprising an elastic member molded with projections on the upper face thereon, and a lift member formed with openings corresponding in shape with the projections to receive the projections, the lift member, having openings therethrough for the reception of securing means, as described.

2. A heel construction, comprising an elastic member formed with projections on its upper surface, and a lift-member having correspondingly shaped openings to receive the projections, the securing means for the heel being located within the projections, whereby the projections will be expanded to completely fill the openings in the lift member.

JAMES A. MURPHY.
